UNITED STATES PATENT OFFICE.

ISIDOR YASSENOFF, OF COLUMBUS, OHIO, ASSIGNOR TO THE SWASH MOTOR WASHER COMPANY, OF COLUMBUS, OHIO, A CORPORATION OF OHIO.

WASHING-MACHINE.

977,772.

Specification of Letters Patent.

Patented Dec. 6, 1910.

Application filed August 14, 1908, Serial No. 448,471. Renewed May 2, 1910. Serial No. 558,912.

To all whom it may concern:

Be it known that I, ISIDOR YASSENOFF, a citizen of the United States, residing at Columbus, in the county of Franklin and State 5 of Ohio, have invented certain new and useful Improvements in Washing-Machines, of which the following is a specification.

My invention relates to improvements in washing machines which are adapted to be 10 operated with the improved reciprocating motor shown and described in my Letters Patent of the United States, No. 894,928, and especially consists in the provision of a reciprocating or rotary device for agitating 15 or stirring the clothing to be washed, which is adapted to be oscillated as the motor operates, especially through the action of a spring or flexible member put under tension by the operation of the motor. I have found 20 that this construction is readily operated and is durable, and provides a washing device which is constructed at a small cost and is very durable and efficient.

Essentially it comprises a depending 25 frame mounted loosely upon an oscillating shaft which latter carries a spring tensioning member for the purpose of giving the frame the desired degree of reciprocation. It is apparent that manually operated means 30 may be provided instead of the motor above mentioned, and I do not confine the use of my improvements to mechanically operated machines.

In the drawings which are hereto attached 35 and hereby made a part of this specification, Figure 1 is a vertical transverse section through the agitator, tub and operating means; Fig. 2 is a perspective of a modified form of agitator construction; Fig. 3 is a 40 view of the band to which the loop or stirring members are attached, having the cross bar thereon.

Referring to the drawings in which the same numeral indicates the same part 45 throughout, 1 indicates a tub member stationed upon the legs or base portion 2, carrying at its upper end a frame 3 forming the support for the motor 4; the cylinder is positioned by means of the set screw 5, and it 50 should be stated that the motor is shown conventionally in the drawing.

The piston 6 is adapted to be reciprocated by fluid entering the external valve chambers 7, which are mounted upon the piston 55 rod 8, and the rack 9, the rack forming prac-

tically an extension of the piston rod, in a manner clearly disclosed in the above mentioned application.

The pinion 10 is fixed on the short vertical shaft 11 which is mounted in the collar or 60 sleeve member 12 carried by the aforesaid frame 3, the shaft being mounted in said collar for reciprocation through the pinion and rack just described.

The band member 14 carries the cross bar 65 13^a provided with a hub 13, whereby it is journaled on the shaft 11; the bar 13^a is shown in Fig. 1, as formed integral with the band 14, but it is apparent that it may be formed separately and secured thereon appropriately. From this band 14 there depend at desired intervals looped fingers or 70 agitators 15, which are twisted as shown at 16 so as to bring the open side of the loop in contact with the clothing as it is swung back 75 and forth. These loops are seen to be free at their lower ends and are securely riveted at 17 in the band 14.

Fixed upon the end of the shaft 11 is a member 18, to the opposite ends of which 80 are attached the spring members 19 and 20 which at their other ends are secured in a desired manner to the frame or band 14 or if desired to the member 13^a. The shaft is oscillated under the influence of the motor; 85 the member 18 is turned first in one direction and then in the opposite direction, thereby tensioning the springs 19 and 20 and exerting a pull thereon around a circle first 90 in one direction and then in another, whereby an oscillating movement in a horizontal plane is imparted to the agitator 14. By these means the articles of clothing are stirred or agitated in both directions in a rapid manner and the cleansing fluid is 95 thrown against the clothing and the clothing against the fluid and a constant agitation is thus kept up to such an extent as to cleanse the clothes very quickly. The depending agitators or fingers are so constructed as not 100 to exert any tearing or any injurious effect upon the fabric, and the loop formation thereof renders them readily cleansed and therefore entirely sanitary.

I have shown in the drawings and have 105 described above, loop members or agitators 15, but I do not confine myself to this form of agitator. It should further be pointed out that in the operation of the washer, the clothing or fabric to be cleansed will be 110

caught by the loop members and swept along thereby, in that way forming a sort of paddle to agitate the water thoroughly. I have not deemed it necessary to show a paddle construction, inasmuch as it will be readily understood.

Free space is provided between the fingers or agitators 15 and the sides and bottom of the receptacle or tub so that the 10 clothing may be rubbed vigorously against the sides and the bottom to hasten the cleansing process. All these advantages herein set out have been demonstrated, and have been found to be of great practical value.

15 In Fig. 2 I have shown another form of agitator member and spring means for actuating the same, comprising an agitator member 21 mounted loosely upon the shaft 22, and having depending from its ends the 20 stirrers 23 and 24, which latter may be made of any form desired. Rigidly mounted on the lower end of the shaft 22 beneath the bar member 21 is a short bar or plate 25 having extensions formed at each of its 25 ends, which may be designated at 26 and 27 and 28 and 29. Spring members shown at 30, 31, 32 and 33 are mounted between the extensions noted and the sides of the bar member 21, which are preferably enlarged 30 to form the shoulders shown at 34. The springs are secured in place in any desired manner. As the shaft 22 is oscillated by the motor, the bar 25 is moved therewith thereby setting up an oscillatory movement in 35 the agitator member 21 which is cushioned and assisted by the spring members. The form of construction shown in Fig. 2 is simpler and less expensive than that shown in Fig. 1, although it is seen that it operates 40 in practically the same manner.

I have found the combination of my improved reciprocating motor with a stirring or agitating member by means of the springs whereby the agitator may be yieldingly os- 45 cillated in a horizontal plane to produce very rapid and complete results in the cleansing

of any ordinary fabric; a specific form of construction is shown in the drawings and herein described but I do not desire to confine myself thereto inasmuch as modified 50 forms of construction lie within the scope of my invention.

What I claim is:

1. A washing machine comprising reciprocating means, a shaft actuated thereby, an 55 agitator rotatably borne upon said shaft, and spring means carried by said shaft for causing said agitator to assume an oscillatory motion.

2. A washing machine comprising recip- 60 roating means, a shaft adapted to be actuated thereby, an agitating member mounted loosely upon said shaft, an arm carried rigidly upon said shaft and having yielding connections with said agitating member 65 whereby the latter is given an oscillatory motion.

3. In a washing machine including reciprocating means and a shaft adapted to be actuated thereby, an agitating member loosely 70 mounted upon said shaft comprising an upper or band portion, depending loop members secured to said band portion and adapted to act as stirrers, an arm rigidly carried on said shaft, spring members connected to 75 the ends of said arm and at their other ends secured to said agitating member whereby the latter is given an oscillatory motion.

4. A washing machine comprising recip- 80 roating means, a shaft actuated thereby, an agitator rotatably mounted upon said shaft, an open looplike stirring member depending from said agitator, and yielding connections 85 between said shaft and said agitator adapted to cause the agitator to assume an oscillatory motion and also to cushion said agitator.

In testimony whereof I affix my signature in the presence of two witnesses.

ISIDOR YASSENOFF.
